(57) **CLAIM**

The ornamental design for a telescoping running stick, as shown and described.

DESCRIPTION

FIG. 1 is a perspective view illustrating an embodiment of a telescoping running stick;

FIG. 2 is a right side elevation view of the telescoping running stick of FIG. 1;

FIG. 3 is a left side elevation view of the telescoping running stick of FIG. 1;

FIG. 4 is a rear elevation view of the telescoping running stick of FIG. 1;

FIG. 5 is a front elevation view of the telescoping running stick of FIG. 1;

FIG. 6 is a top plan view of the telescoping running stick of FIG. 1;

FIG. 7 is a bottom plan view of the telescoping running stick of FIG. 1;

FIG. 8 is a perspective view illustrating another embodiment of a telescoping running stick;

FIG. 9 is a right side elevation view of the telescoping running stick of FIG. 8;

FIG. 10 is a left side elevation view of the telescoping running stick of FIG. 8;

FIG. 11 is a rear elevation view of the telescoping running stick of FIG. 8;

FIG. 12 is a front elevation view of the telescoping running stick of FIG. 8;

FIG. 13 is a top plan view of the telescoping running stick of FIG. 8; and,

FIG. 14 is a bottom plan view of the telescoping running stick of FIG. 8.

The broken lines depict portions of the article that form no part of the claimed design.

1 Claim, 8 Drawing Sheets
